UNITED STATES PATENT OFFICE.

PATRICK J. CONNOLLY, OF JERSEY CITY, NEW JERSEY, ASSIGNOR TO A. KIMBALL COMPANY, OF NEW YORK, N. Y., A CORPORATION OF NEW YORK.

MARKING-TICKET.

1,259,723.

Specification of Letters Patent. Patented Mar. 19, 1918.

Application filed April 11, 1917. Serial No. 161,127.

To all whom it may concern:

Be it known that I, PATRICK J. CONNOLLY, a citizen of the United States, and resident of Jersey City, county of Hudson, State of New Jersey, have invented an Improvement in Marking-Tickets, of which the following description, in connection with the accompanying drawing, is a specification, like characters on the drawing representing like parts.

This invention relates to improvements in marking clips and the object thereof is to provide a marking ticket or tag which may be applied easily to an article of merchandise and which will not mutilate the material to which it is attached.

The usual devices used to mark textile articles of merchandise are known as pin tickets and comprise a card to receive the notations of cost, sale price, style, etc. These cards are provided with pins or staples adapted to be thrust through the material to which they are to be attached.

The present invention contemplates the provision of means for securing the card to the material without the necessity of having the affixing device penetrate the material and comprises a card which may be of the usual type having a recess with means for forcing a bight of material to be marked into said recess and clamping the same therein.

A preferred embodiment of the invention is shown in the accompanying drawings in which,

Figure 1 is a top plan view illustrating the marking clip applied to a piece of fabric,

Fig. 2 is a reverse view of the under side of the ticket and affixing device, and,

Fig. 3 is a longitudinal sectional view through the ticket and the affixing device showing the latter clamping a bight of the material in the recess in the ticket.

The preferred embodiment of the invention which is illustrated in the drawings comprises a ticket 1 of stiff material such as cardboard the face of which may be provided with notations like those ordinarily used upon pin tickets. A recess or slot 2 is formed in the card preferably parallel with and near one end, into which a bight of material to be marked may be forced. This recess may be a depression from the reverse side of the card toward the face thereof but

preferably is a slot extending through the card.

The affixing device for clamping the bight of material into the slot is in the form of a stiff, pliable, non-resilient member preferably extending beyond the end of the card a sufficient distance to embrace a considerable portion of the material to which the card is to be affixed, the end of the affixing member being provided with a projection which may be utilized to force a bight of the material into the recess of the card and in coöperation with the walls of the recess clamp the same therein.

The affixing member may be an extension of the body of the card with or without a reinforcing member but preferably is in the form of a metallic clip attached to the card adjacent its end and bent to form a loop, one limb of which extends beyond the end of the card and the other limb of which extends substantially parallel to the reverse face of the card and is provided at its extremity with an offset portion so positioned that when the limbs of the clip are squeezed together the end will enter the recess in the card.

As illustrated in the accompanying drawing the metallic clip 3 has a circular end 4 provided with anchoring prongs 5 which are thrust through the card and clenched. A limb 6 extends from the circular portion 4 a short distance beyond the end of the ticket and in substantial parallelism with the face of the card.

The affixing member is bent back upon itself to form a loop 8 the limb 9 of which extends over the reverse face of the card. The end portion of the limb 9 is offset or bent laterally substantially at right angles to form a locking member 10, and the extremity 11 of the locking member 10 preferably is doubled tightly upon itself so that the locking member presents a smooth curved surface 12 to engage the material to which the marking clip is applied.

In using the device the reverse face of the card is placed against the material and a single or doubled fold of the material thrust beneath the limb 9 of the affixing device. The limbs of the clip are then pressed together until the offset end 12 of the limb 9 enters the recess 2 in the card, carrying with it the bight of the material 13. The affixing device of course is of a pliant

non-resilient material which when once bent into place will remain there, so that the bight of material will be clamped within the recess.

5 When the bight of material is thus locked in the card the strains are transversely of the looped portion of the bight and do not tend to bend back the limb 9 of the affixing member so that the card will be firmly retained upon the material until it is desired 10 to remove it.

All that is necessary to remove the marking ticket from the material is to lift the rear limb 9 of the affixing device from the 15 card until the offset end portion 10 is withdrawn from the recess whereupon the bight of material can be readily withdrawn from said recess.

By this construction the card may be 20 fixed to the most delicate fabrics without injuring the same as the end of the affixing device does not penetrate the fabric and has no sharp points or ragged edges which will damage the fibers of the material.

25 It is to be understood that the embodiment of the invention disclosed herein is illustrative in character but is not restrictive and that the same may be embodied in other forms within the meaning and scope of 30 the following claims.

Having thus described my invention what I claim as new and desire to secure by Letters Patent is;

1. A marking ticket comprising a card 35 having a recess and a stiff pliable member secured thereto having a free end adapted to force a bight of the material to be marked into said recess and to clamp the same therein.

40 2. A marking ticket comprising a card

Copies of this patent may be obtained for five cents each, by addressing the "Commissioner of Patents, Washington, D. C."

having a recess and a reversely bent stiff pliable member extending from said card and having a free end adapted to force a bight of the material to be marked into said recess and in coöperation with the walls of 45 said recess to clamp said material therein.

3. A marking ticket comprising a card, a stiff pliable member extending beyond the edge of said card and reversely bent to present a loop, the free end of said member having an offset portion opposite said recess adapted to force a bight of the material to be marked into said recess and in coöperation with the walls of said recess to clamp 50 said material therein. 55

4. A marking ticket comprising a card having a recess, a pliable metallic clamping member secured to said card and bent to form a loop extending beyond the end of the card and a limb extending along the reverse face of the card at a distance therefrom and provided with an offset end positioned to enter said recess and in coöperation 60 with the walls of the recess to clamp a bight of the material therein. 65

5. A marking ticket comprising a card having a recess, a pliable metallic clamping member secured to said card and bent to form a loop extending beyond the end of the card and having a limb extending along the reverse face of the card at a distance therefrom and provided with an offset portion 70 bent back upon itself to present a smoothly rounded end positioned to enter said recess and in coöperation with the walls 75 of said recess to clamp a bight of the material therein.

In testimony whereof, I have signed my name to this specification.

PATRICK J. CONNOLLY.
